[57] **ABSTRACT**

A stackable housing for electronic equipment and the like, characterised in that a first housing is provided at its bottom with shoulder means adapted for pivotal connection with corresponding means on the upper forward edge portion of a second housing arranged therebeneath. Snap-lock means are provided for removably connecting another lower portion of the first housing with another upper portion of the second housing, thereby locking said housings against sliding movement relative to each other.

STACKABLE HOUSINGS FOR ELECTRONIC EQUIPMENT

This invention relates generally to stackable housings for electronic equipment. When constructing measuring, control and regulating systems and similar arrangements, the requirement frequently arises of connecting in a building block manner further units to a basic unit already provided. Preferably this is accomplished in such a manner that the individual units, each disposed in a housing, are fitted one above the other and can be separated again without difficulty.

This arrangement gives rise to the problem, however, of securing the individual housings in position relative to each other. For this purpose, many housings are simply provided with rubber feet, but these do not satisfactorily achieve the desired purpose, *inter alia* for the reason that there is no positive location when stacking a plurality of housings. The individual housings must be aligned by hand and eye but, nonetheless, are then not sufficiently prevented from slipping (for example, when subjected to vibration).

Accordingly, the primary object of the present invention is to provide a stackable housing for electronic equipment, comprising top, bottom and wall portions, a lower edge of the housing being so constructed that when it co-operates with an upper edge of a second housing said lower edge acts as a pivot mounting, at least one snap lock means being provided which, after engagement, grips an upper edge portion of the second housing such that further pivotal movement of the two housings relative to each other is prevented.

A more specific object of the invention is to provide a housing which can be used individually or can be stacked with further similar housings to form a system. When the housings are stacked they can be secured in position in all directions without the assistance of additional means. The exteriors of the housings can of course be made of pleasing appearance.

A preferred embodiment of the housing according to the invention has at the lower edge of its forward side a retaining bar which both acts as a support and also, by means of a groove formed therein, engages around the slightly projecting forward portion of the cover plate of a housing below the first mentioned housing. The retaining bar extends over the entire inside width of the housing and in this way, in conjunction with the forwardly extended side walls, prevents the housing being displaced laterally. If the retaining bar is of a suitable configuration, it can be used at the same time as a symbol-bearing panel, for example for carrying typed designations etc, by means of adhesive label strips.

Disposed at the rearward lower edge is at least one, but preferably two, supports each of which incorporate a snap lock including an element which is pivotable about a pin disposed adjacent the centre of the element and which is urged away from the housing at the top (for example, by a leaf spring) and is thus urged towards the housing at the bottom. This element engages a slightly projecting edge portion of the cover plate of a housing located therebelow. The lower edge of the pivotable element preferably terminates above the stationary surface of the rigid part of the supports, in order to prevent loading of the pivot pin of an individual housing or a lowermost housing.

In a further embodiment of the housing according to the invention, there is provided a pivotable support bar

which, when not in use, is preferably held against the underside of the housing by suitable design of the bar and its mountings. The support bar makes it possible, when required, for the individual housing or the group of housings to be set up in an inclined position at a given angle, thereby permitting easier reading or operation.

Other objects and advantages of the invention will become apparent from a study of the following specification when considered with reference to the accompanying drawing, in which :

FIG. 1 shows a bottom plan view of the housing

FIG. 2 is a sectional view taken along line II-II of FIG. 1,

FIG. 3 is an elevation view of a rearward support foot,

FIG. 4 is an enlarged section taken on line IV-IV of FIG. 1, and

FIG. 5 is a perspective view of two stacked housings.

The sections of FIGS. 2 and 4 are drawn such as to correspond to the normal position of the housing.

Referring now to the drawings, the housing comprises a combined base and rear plate 8, a front plate 9 and a cover plate 10 which includes orthogonally arranged flange portions that define the sides of the housing. The cover plate 10 is of a configuration such that both at the top and at the sides it includes edge portions that extend forwardly and rearwardly by a few millimeters beyond the front and rear faces. The front plate 9 carries operating or indication elements, while the rear plate 8 carries the necessary plug and socket connections.

The front plate 9 and the cover plate 10 are secured to the base plate 8 by screws 11 and 12 which pass through spot-welded angle plates 13. The screws 11 also hold a retaining bar 14 which pivotally carries a support bar 16 in partly closed recesses 15. The support bar 16 is pivotable about its two retained end portions 17 (FIG. 2) and is fixed in its horizontal rest position by the recessed portions 18 in the open part of the recesses 15, by virtue of its spread action after insertion under an initial stress (FIG. 4).

In addition to a support portion 19 which acts as a foot, the retaining bar 14 also has a symbol-bearing panel 20 and a groove 21 in which, when a plurality of housings are set one upon the other, the forwardly projecting part of the cover plate 10 of the next lower housing is held. The length of the retaining bar 14 substantially corresponds to the inside measurement between the flange portions of the cover plate 10 which partly overlap the retaining bar 14, so that the housings are held laterally relative to each other.

Two feet 22 are secured by respective screws 23 to the rear of the base plate 8 at the outer ends thereof, each foot 22 lying against the inward side of the flange portions of the cover plate 10. Associated with each foot 22 is snap lock means formed by a pin 24 on which there is pivotally mounted a retaining element 26 which has a projecting lug 25 and which is arranged in a corresponding central recess in the foot 22. Clamped between the foot 22 and the base and rear plate 8, and held in position by the screw 23, is a leaf spring 27 which urges the upper portion 28 of the retaining element 26 outwardly and thus the lower portion carrying the lug 25 inwardly into engagement with the cover plate 10 of the lower housing, thereby urging the above mentioned lower portion against the lower housing.

Thus, when a plurality of housings are stacked one upon the other, they are secured in position by the snap locks and the groove 21 in the retaining bar 14.

In order to place a further housing upon a lower housing, the former housing is moved, in a slightly inclined position, rearwardly towards the lower housing until the groove 21 engages into the cover plate 10 of the lower housing, whereupon the first mentioned housing is pivoted about the groove 21 until snap lock means are snapped into position.

To remove an upper housing, the upper portion of the two retaining elements 26 are pressed slightly inwardly (that is, towards the housing) against the spring force of the leaf springs 27, whereupon the housing is slightly lifted at the back and drawn forwardly so that it comes out of the retaining groove 21, and then is lifted off.

When setting up only a single housing, or in the case of the lowermost housing when a plurality of housings are stacked one upon the other, the pins 24 are not subjected to load as the lower portion carrying the lug 25 is so constructed that it has a certain ground clearance relative to the support surfaces of the feet 22 (FIG. 3).

In order to improve the slip-proof capacity of the housings on a smooth support surface, the supports 16 can be provided with non-slip rings 29, comprising for example rubber (FIG. 1).

Various modifications can be made without departing from the invention as defined by the appended claims. Thus, for example, instead of a single continuous retaining bar 14, there could be provided two or more correspondingly shaped individual retainers. It would also be possible for the snap locks to be positioned at the sides and co-operate with a suitably shaped cover plate, when for example the rear plate is to be kept entirely free for plug and socket connections. Other modifications may be made in the described apparatus without deviating from the inventive concept.

What is claimed is:

1. A stackable housing for electronic equipment, comprising
  - a. a first housing having bottom, front, side, rear and top walls, said top and side walls projecting forwardly slightly beyond said front wall, said top wall projecting forwardly slightly beyond said rear wall;

and

- b. means for interconnecting said first housing with a similar second housing arranged in stacked relationship therebeneath, said interconnecting means including
  1. shoulder means on said first housing for pivotally connecting the forward portions of said first and second housings, said shoulder means including a depending retaining bar connected with the forward portion of said bottom wall and containing a rearwardly facing groove for pivotally receiving the forwardly projecting top wall portion of the second housing, said retaining bar terminating at both ends in juxtaposition to the forwardly projecting side wall portion of said second housing, respectively, thereby retaining said base in fixed lateral position with respect to the second housing; and
  2. snap lock means for releasably locking the rear portion of said first housing with the rearwardly projecting top wall portion of said second housing, said snap lock means including
    - a. at least one centrally pivoted retaining element having a lug on the lower end, and
    - b. spring means for biasing said retaining element toward a position in which said lug hooks over the rearward lip of the second housing top wall and for permitting said retaining element to be manually rotated to a position in which said lug clears the rearward lip of the second housing top wall when said base is rotated about the forward lip of the second housing.
2. A stackable housing as defined in claim 1, wherein said retaining bar includes front foot means for engaging a first supporting surface to space the front portion of said base a predetermined distance from the first supporting surface, and further wherein said snap lock means includes rear foot means for engaging a second supporting surface to space the rear portion of said base at said predetermined distance from the second supporting surface, said rear foot means including a pair of foot elements extending below the lower most extremities of said retaining element.
3. A stackable housing as defined in claim 1, wherein said snap lock means includes a pair of centrally pivoted retaining elements.
